GOLF BALL

Frank S. Martin, Cranston, R.I., and Thaddeus A. Pietraszek, Waterbury, Conn., assignors to Uniroyal, Inc.

Filed July 28, 1972, Ser. No. 276,218

Term of patent 14 years

The term of this patent subsequent to Sept. 18, 1987,
has been disclaimed

Int. Cl. D21—02

U.S. Cl. D34—5 QQ

FIG. 1 is a top plan view of a golf ball, showing our new design;

FIG. 2 is a front elevational view of the FIG. 1 ball;

FIG. 3 is a view of a typical portion of the FIG. 1 view of the ball but developed and shown on a plane surface; FIG. 4 is a view, to an enlarged scale, of a depression having a spherical base; and

FIG. 5 is a sectional view to an enlarged scale, through the cover of the ball and a portion of the interior winding of the ball to represent a depression having a spherical base.

If the ball as shown in FIG. 1 were rotated 180° in the direction of the arrow from top to bottom, the view then on top would appear identical with FIG. 1. Also, if the ball shown in FIG. 2 were rotated in the direction of the

arrow from left to right in five 72° increments each such elevational view of the ball would appear identical with FIG. 2.

We claim:

The ornamental design for a golf ball, substantially as shown and described.
